METHOD OF ATTACHING SOLES TO SHOES

Sidney J. Finn, Beverly, Mass., assignor to United Shoe Machinery Corporation, Flemington, N. J., a corporation of New Jersey

Application December 13, 1941, Serial No. 422,808

13 Claims. (Cl. 12—142)

This invention relates to methods for use in cement-attaching soles to shoes and particularly to methods for obtaining close shanks.

It will be understood that, when soles are to be cement-attached to shoes by means of pressure-responsive cement, if the forepart of the sole is located with respect to the forepart of the shoe and then the heel part of the sole located with respect to the heel-seat of the shoe, the shank portion of the sole will bridge across the curve of the shank, and the length of the sole from the ball to the heel-seat will be less than the distance measured along the curve of the shank. Consequently, when the shank portion of the sole is forced against the shank of the shoe the material of the sole has to stretch in order to equal in length the curve of the shank. This, of course, puts a longitudinal tension on the shank portion of the sole which tends to cause it to pull away from the shank of the shoe, a condition which militates against the production of shoes having permanently close shanks.

Objects of this invention are to provide a method whereby the above disadvantageous conditions may be overcome by assuring that a sufficient length of material will be provided in the shank portion of the sole to correspond substantially to the length measured along the curve of the shank.

In the practice of the present method the attaching faces of the shoe and sole are provided with cement which will adhere when the parts are brought in contact, sufficiently at least to prevent the parts from slipping relatively to each other. The forepart of the sole is located, for example, by hand upon the forepart of the shoe, this operation being usually referred to as "spotting" the sole. The shank portion of the sole is then bent away from the shank portion of the shoe and the heel end of the sole "spotted" upon the heel-seat of the shoe.

The distance that the sole is separated from the shank will be sufficient to provide a length measured along the sole which will correspond to or slightly exceed the length measured along the curve of the shank between the respective contact points of the sole and shoe. For this purpose the illustrated apparatus is provided which comprises a pair of fingers relatively movable heightwise of the shoe and adapted, when in proximity to each other, to be located between the shoe and sole at the shank portion, the fingers being separable a predetermined amount which may be varied for different shoes. The illustrated apparatus is disclosed and claimed

per se in my application, Serial No. 470,189, filed December 26, 1942, as a division of this application. The next step is to apply pressure to the forepart and heel portion of the shoe without disturbing the outward or downward curvature of the shank portion. This insures such adhesion at the toe and heel of the shoe that the sole cannot slip with respect to the shoe. Now the shank portion of the sole is forced against the shank portion of the shoe and uniform pressure is applied to the entire shoe bottom.

These pressure-applying steps may be carried out by means of the illustrated apparatus which is disclosed and claimed per se in my application, Serial No. 470,188, filed December 26, 1942, as a division of this application, and which comprises a resilient pad to receive the sole of the shoe, the shank portion of the pad being normally bent away from the shoe sufficiently to accommodate the outwardly bulging shank portion of the sole. The apparatus is provided with abutments engaging the forepart of the shoe and the heel end of the last which are operated to apply predetermined pressure to the shoe, thus firmly seating the forepart and heel-seat of the sole against the shoe to cause adhesion. After this pressure has been applied, means is provided to force the shank portion of the pad up against the shank portion of the shoe and then, by means of an inflatable bag covering the entire shoe bottom, the pad is forced with uniform pressure against the entire shoe bottom, thus insuring permanent cement-attachment of the shank portion as well as the remainder of the sole in close-fitting relation to the upper of the shoe.

In the drawings,

Fig. 1 is a side elevation of apparatus designed to effect a predetermined separation of a shoe and sole at the shank portion while the end portions of the shoe and sole are held by the operator's fingers;

Fig. 2 is a sectional view on the line II—II of Fig. 7;

Fig. 3 is a view similar to Fig. 1, the apparatus being shown in inoperative position;

Fig. 4 is a plan view of the apparatus shown in Fig. 1;

Fig. 5 illustrates diagrammatically a cement sole attaching machine equipped with the present invention;

Fig. 6 is a side elevation, partly in section, of the operating instrumentalities of a cement sole attaching machine equipped with the present invention; and

Fig. 7 is a detail view similar to Fig. 6 showing the parts in operative position.

The first steps of the method may be practised by use of apparatus such as that illustrated in Figs. 1, 3 and 4 which comprises a pair of fingers 10, 12 carried respectively by a lever 14 and an arm 16. The fingers 10, 12 may, as shown, be right-angular prisms with their longest faces in contact, the right angles being disposed at the top and bottom. The arm 16 carrying the finger 12 is rigidly mounted or formed as an integral offset from a sleeve 18 fixed to a vertical shaft 20 mounted for rotation in a bearing 22 formed in a bracket having an ear or ears such as 24 adapted to be secured to a suitable fixed support such, for example, as the left-hand side of a machine for pressing a shoe and sole together. The shaft 20 is held from upward movement by a washer 26 secured by a screw 28 to the shaft. The lever 14 carrying the finger 10 is pivoted at 30 between ears 32 offset (Fig. 4) from the sleeve 18 which is carried by the shaft 20. Between its ends the lever 14 carries a vertical slideway 34 in which the sliding block 36 is mounted. An adjusting screw 38 is threaded into the upper part of the slideway in position to engage the block 36 and limit its upward movement with respect to the lever 14. To the block 36 is pivoted one end of a link 40. A lever having three arms 42, 44 and 46 is pivoted at 48 to the finger arm 16, the lever arm 42 having ears between which the lower end of the link 40 is pivoted. A pin on the lever arm 46 is connected by a tension spring 50 to a pin on the finger arm 16, the spring holding the link 40 and the arm 42 in the angular position shown in Fig. 3 with the fingers 10, 12 together.

In the bearing 22 is formed a vertical slideway in which is fitted a slide 52 connected at 54 (Fig. 1) to a treadle rod 56. The slide 52 carries a roll 58 which engages an inclined slot 60 in the sleeve 18 so arranged that upward movement of the slide will swing the sleeve and the fingers which it carries about the axis of the shaft 20 from right to left. The upper portion of the slot 60 is vertical and when the roll 58 reaches this portion of the slot rotation of the fingers creases and a lateral projection 62 (Fig. 4) carried by the slide 52 engages a roll 64 on the lever arm 44. Further upward movement of the slide then straightens the toggle formed by the link 40 and the arm 42. The block 36 is thus raised and, after engaging the screw 38, separates the fingers 10, 12, by swinging the finger lever 14 about its axis 30, a predetermined amount, depending on the setting of the screw, upward movement of the slide 52 being limited by engagement of the roll 58 with the upper end of the slot 60.

In practising the present method, a lasted shoe S (Fig. 1) and an outsole O are prepared for cement attachment by coating the overlasted portion of the upper and the marginal portion of the attaching face of the sole, including the heel-seat portion of the shoe and sole, with pressure-responsive cement such as the polymerized chloroprene cement disclosed in United States Letters Patent No. 2,061,296, granted November 16, 1936, on application of Walter H. Wedger, the cement being allowed to dry until it is in such condition that the shoe and sole will stick together when brought into contact. The operator then locates the forepart of the sole with respect to the forepart of the shoe and presses them together and, while holding the shank-and-heel portion of the sole somewhat separated from

the shoe, depresses a treadle connected with the slide 52, causing it to move upwardly, thus swinging the fingers 10, 12 into position between the shoe and sole. Further movement of the treadle 5 causes the fingers to separate a predetermined amount, depending on the setting of the screw 38. The rear end of the sole is then pressed against the heel-seat of the shoe, as shown in Fig. 1, the amount of separation of the fingers being so adjusted that the distance measured along the sole from the point of contact with the shoe at the ball to the point of contact with the shoe at the heel end will be at least equal to, and may exceed, the distance measured between these points along the shoe bottom. If the length of the shank portion of the sole exceeds the length measured on the shoe against which it is to be laid, the act of forcing the bulged portion of the sole against the shank will place that portion under endwise compression so that it will tend to lie all the more firmly against the shank of the shoe.

The shoe is now ready for treatment by a sole pressing machine having a novel type of pad box, which will now be described.

The general organization of the machine, which may in most respects be similar to that disclosed in United States Letters Patent No. 2,301,205, granted November 10, 1942, on my application, is shown diagrammatically in Fig. 5. The machine is provided with a novel pad box construction shown in Figs. 2, 6 and 7.

The pad box has a fixed forepart portion 70 secured to a frame 72 and an adjustable heel portion 74 which rests on a block 76 pivoted to a lever 78. The lever is U-shaped, its ends being fulcrumed at 80 on the frame 72, and its forward end, which forms the loop of the U, rests on a slide 82 which is mounted in a bracket 84 secured to the frame 72. The slide 82 is arranged for upward and outward movement and is held against downward movement by a pawl 86 engaging teeth 88 on the front side of the slide. The pawl 86 is held in engagement with the teeth 88 by a spring 90 and has a finger-piece 92 by which it may be released so that the operator, by grasping a handle 94, may move the slide and the forward end of the lever 78 up and down. The end of the heel portion 74 of the pad box next to the shank is connected at each side to a branch of the U-shaped lever 78 by a link 96, as is best shown in Fig. 2. Movement of the slide 82, therefore, will adjust the rear part 74 of the pad box relatively to its forepart to adapt the pad for shoes that are designed to receive heels of different heights, that is, for the spring of the last.

Between the rear part 74 and the forepart 70 of the pad box is a shank portion or plate 98 which is arranged to move vertically into and out of position to fill the space between them. In the pad box is a solid rubber pad 100, and an inflatable pad 102 is arranged beneath the pad 100 and connected with a pipe 104 through which fluid under pressure may be supplied to inflate the pad. The shank portions of both pads 100 and 102 are preferably so formed that they normally project downwardly between the heel part and the forepart of the pad toward the shank plate 98. Extending downwardly at each side of the pad box 70 is a plate 106. The upper corners of each plate are pivoted respectively to the heel part 74 at 108 and to the forepart 70 at 110 (Fig. 7), the plates thus forming links between the forepart 70 and the heel part 74. The plates 106 extend down between the branches of the U-shaped lever 78 (Fig.

2) and are spaced apart sufficiently to permit movement of the shank plate 98 between them. Projecting from each side of the shank plate 98 is a pin 112 guided in a slot 114 provided in one of the plates 106, the slots being perpendicular to a plane joining the pivots 108, 110. On the under side of the end of the plate 98 next to the forepart 70 are bifurcated ears 116 to which the upper ends of toggle links 118 are pivoted by pins 120. The lower ends of the links 118 are each pivoted by a rod 122 to bifurcated ears 124 formed on a number 126 which constitutes the lower links of a double toggle of which 118, 118 form the upper links. The member 126 has at each side an ear 128 which is pivoted by a pin 130 to one of the plates 106. Rearwardly of the double toggle 118, 126 is another pair of similar toggles the upper links 132 of which are pivoted at 134 (Fig. 7) to the shank plate 98 and the lower links 136 of which are pivoted at 138 one to each of the plates 106. The joint of the double toggle 132, 136 is formed by a rod 140 which passes through the adjacent ends of both pairs of links 132, 136 and is connected by a tension spring 142 to the block 76, the spring tending to break the toggle in a forward direction. The rod 140 forming the joint of the forward toggles is connected by links 144 to the rod 122 which forms the joint of the rearward toggles 118, 126. The links 144 cause the forward and rearward toggles to act in unison and, when straightened, to effect upward movement of the shank plate into the gap between the adjacent ends of the forepart 70 and the heel part 74 of the pad box.

Since the upper corners of each plate 106 are pivoted one at 103 to the heel part 74 and the other at 110 to the forepart 70, these plates partake of the heightwise adjustment of the heel part 74 to accommodate lasts of different spring, and the shank plate 98, since it is carried by the plates 106 and is guided by the pins 112 in the slots 114 which extend perpendicular to a line joining the pivots 108, 110, will always be moved by operation of the toggles in a direction perpendicular to the shank portion of the pad, that is, perpendicular to a line joining the pivots 108, 110.

In the middle of the member 126 (Fig. 2) is a pair of ears 146 between which is a rack bar 148 and through which and the rack bar the rod 122 passes, the rack bar being moved longitudinally when the toggles are operated. Teeth 150 on the rack bar (Figs. 6 and 7) engages a pinion 152 secured to the stem of a rotary valve 154 in the pipe 104, the arrangement being such that when the toggles are nearly straight the valve will be opened. A guide 155 for the rack 148 is pivoted on the valve stem and serves to hold the rack in engagement with the pinion 152.

The member 126 has a lateral extension 156 carrying a roll 158 upward pressure on which will straighten the toggles and raise the plate 98 as above explained. Beneath the roll 158 is a flat plate 160 extending lengthwise of the pad box and narrow enough to pass between the lower pivots of the toggles to engage the roll 158. The plate 160 is carried by a fluid-operated plunger 162 mounted in a cylindrical recess 164 in the bracket 84 and held from turning by a pin 166 on the plate 160, the pin sliding in a vertical hole in the bracket. The lower end of the cylinder 164 communicates with a pipe 168 through which fluid under pressure may be supplied to operate the plunger.

Referring now to Fig. 5, the shoe, with its sole located at the forepart and heel and with its

shank portion bent away from the shoe a predetermined amount, as may be done for example by the separation of the fingers 10, 12, is placed upon the pad 100 with the shank portion of its sole occupying the depression in the shank portion of the pad. In the base of the machine is an oil reservoir 170 from which a rotary pump 172 supplies oil to a pipe 174 leading to a slide valve 176 at a pressure determined by a pressure control valve 178. Overflow from this valve is led to another pressure control valve 180 which supplies oil at a lower pressure to a pipe 182 leading to a slide valve 184. The slide valve 176 is connected by a link 183 to a treadle 186 pivoted at 188. When the treadle 186 is depressed to lift the valve 176, oil is admitted under high pressure to a cylinder 192, causing a plunger 194 in the cylinder to push up on a rod 196 which is pivoted to the mid portion of a lever 198 fulcrumed at 200 to a cam 202 having a fixed pivot at 204. A pin 206 on the end of the lever opposite its fulcrum is connected by a strong tension spring 208 to a fixed pin 210. Upward movement of the rod 196 acts at first to turn the cam 202 which, acting on a block 212, turns a lever 214 pivoted at 216 counterclockwise to cause abutments 218, 220 carried thereby to engage respectively the last and the forepart of the shoe and to press the shoe down upon the pad, thus applying pressure to the forepart and heel part of the shoe but not to the shank portion which is at this time unsupported, the shank portion of the sole lying in the depression in the shank portion of the pad 100. When a pressure determined by the tension on the spring 208 has been applied to the shoe, the spring yields, allowing the lever 198 to turn on its fulcrum 200 and lift a link 222 which is pivoted at its lower end to an intermediate portion of a lever 224 fulcrumed at 226. The opposite end 40 of the lever 224 is connected to the valve 184 which is lifted by the lever to open the valve, thus admitting oil from the pipe 162 at reduced pressure to the pipe 168 connected to the cylinder 164. The pipe 168 has a branch 228 leading to a cylinder 230 in which is a double piston 232. The lower end of the cylinder receives oil under pressure from the pipe 228, and the upper portion of the cylinder is filled with water including the pipe 104 which leads to the inflatable pad 102.

When the slide valve 184 is opened as described, pressure will be delivered to the pipe 168 to cause the plunger 162 to rise and engage the roll 158, causing the toggles to straighten and the shank plate 98 to move into the gap between the forepart 70 and the heel part 74 of the pad box. Just before the toggles 118, 126 reach their straightened position, the valve 154 in the pipe 104 will be opened by the action of the rack bar 148 on the pinion 152, thus permitting the pressure in the pipe 228 to act on the piston 232 and force water through the pipe 104 into the inflatable pad 102 whereby uniform pressure is applied to the entire shoe bottom. The toggles supporting the shank plate 98 become fully straightened before any substantial pressure is built up in the inflatable pad and serve to support the shank plate rigidly while the shoe is under pressure.

To bridge any gap which may occur between the shank plate 98 and the heel part 74 of the box, a thin plate 234 (Fig. 7) is pivoted at 236 to the heel part 74 of the box and at its opposite edge overlies the adjacent edge of the shank plate 98.

Having thus described my invention, what I

claim as new and desire to secure by Letters Patent of the United States is:

1. That improvement in methods of attaching soles to shoes which consists in holding the shank portion of the sole bulged away from the shank portion of the shoe, and while the shank portion is so held applying pressure to the shank portion of the sole to cause the outwardly bulged portion to engage the shank portion of the shoe.

2. That improvement in methods of attaching soles to shoes which consists in pressing the end portions of the sole against the shoe bottom while the shank portion of the sole is bulged outwardly with respect to the shank portion of the shoe, applying pressure to the shank portion of the sole to cause the outwardly bulged portion to engage the shank portion of the shoe, and then applying uniform pressure to the entire shoe bottom.

3. That improvement in methods of attaching soles to shoes which consists in spotting the sole at one end portion of the shoe, bending the shank portion away from the shank portion of the shoe, spotting the opposite end portion of the sole on the shoe bottom, and applying pressure first to the end portions of the shoe and then to the shank portion.

4. That improvement in methods of attaching soles to shoes which consists in spotting the sole at one end portion of the shoe, bending the shank portion away from the shank portion of the shoe, spotting the opposite end portion of the sole on the shoe bottom, and applying pressure first to the end portions of the shoe, then to the shank portion, and finally applying uniform pressure to the entire shoe bottom.

5. That improvement in methods of attaching soles to shoes which consists in providing pressure-responsive cement on the attaching faces of a shoe and sole, locating the forepart of the sole with respect to the forepart of the shoe, causing them to adhere, separating the shank portion of the sole from the shank portion of the shoe a predetermined distance, locating the heel part of the sole with respect to the heel-seat of the shoe, causing it to adhere, applying pressure to the forepart and heel part of the shoe, forcing the shank portion of the sole against the shank portion of the shoe, and then applying pressure to the entire sole area.

6. That improvement in methods of attaching soles which consists in providing pressure-responsive cement on the attaching faces of a shoe and sole, locating the forepart of the sole with respect to the forepart of the shoe, causing them to adhere, separating the shank portion of the sole from the shank portion of the shoe, locating the heel part of the sole with respect to the heel-seat of the shoe, causing it to adhere, applying pressure to the forepart and heel part of the shoe, forcing the shank portion of the sole against the shank portion of the shoe, and then applying uniform pressure to the entire sole area.

7. That improvement in methods of attaching soles to shoes which consists in pressing the toe portion of a sole against a shoe bottom, locating the shank portion of the sole away from the shank portion of the shoe, while the shank portion is so located pressing the rear end of the sole against the heel-seat of the shoe, and then applying pressure to the shank portion of the sole to cause it to engage the shank portion of the shoe.

8. That improvement in methods of attaching soles to shoes which consists in pressing the end

portions of a sole having pressure-responsive cement thereon against the end portions of a shoe bottom while the shank portion of the sole is bulged outwardly with respect to the shank portion

5 of the shoe to an extent such that the distance measured along the sole between the contact points of the shoe and sole will substantially equal the distance measured along the shoe bottom between said points, applying pressure to the shank portion of the sole to cause the outwardly bulged portion to engage the shank portion of the shoe, and then applying pressure to the entire shoe bottom.

9. That improvement in methods of attaching soles to shoes which consists in bending the shank portion of a sole away from the shank portion of a shoe, while the sole is so bent pressing the forepart and the heel part of the sole against the shoe bottom, and then applying pressure to the shank portion of the sole to cause the outwardly bent portion to engage the shank portion of the shoe.

10. That improvement in methods of attaching soles to shoes which consists in pressing the end portions of a sole having pressure-responsive cement on its attaching faces against a similarly cemented shoe bottom, while the shank portion of the sole is bulged outwardly with respect to the shank portion of the shoe applying pressure to the shank portion of the sole to cause the outwardly bulged portion to adhere to the shank portion of the shoe, and then applying uniform pressure to the entire shoe bottom.

11. That improvement in methods of attaching soles to shoes which consists in preparing a sole with polymerized chloroprene cement on the margin of its attaching face in condition to adhere under pressure to a similarly prepared surface on a shoe, spotting the sole at one end portion of the shoe bottom, bending the shank portion away from the shank portion of the shoe, spotting the opposite end portion of the sole on the shoe bottom, and applying pressure first to the end portions of the shoe and then to the shank portion.

12. That improvement in methods of attaching soles to shoes which consists in providing pressure-responsive cement on the attaching faces of a shoe and sole, locating the forepart of the sole with respect to the forepart of the shoe, causing them to adhere, separating the shank portion of the sole from the shank portion of the shoe a predetermined distance, locating the heel part of the sole with respect to the heel-seat of the shoe, causing them to adhere, applying pressure to the forepart and heel part of the shoe without disturbing the outwardly bulged position of the shank part of the sole, then forcing the shank portion of the sole against the shank portion of the shoe, and applying uniform pressure to the sole.

13. That improvement in methods of attaching soles to shoes which consists in providing pressure-responsive cement on the attaching face of a shoe and sole, spotting the forepart of the sole upon the forepart of the shoe, separating the central portion of the shank of the sole from the central portion of the shank of the shoe a predetermined distance, spotting the rear part of the sole upon the heel-seat of the shoe whereby the shank portion of the sole is in outwardly bulged relation to the shank of the shoe, forcing the outwardly bulged shank portion of the sole against the shank portion of the shoe, and applying uniform pressure to the sole.
